INVENTOR
John W. Aymar, Jr.

BY C. P. Goepel,
ATTORNEY

UNITED STATES PATENT OFFICE.

JOHN W. AYMAR, JR., OF NEW YORK, N. Y.

RESILIENT HEEL.

Application filed September 27, 1920. Serial No. 413,680.

To all whom it may concern:

Be it known that I, JOHN W. AYMAR, Jr., a citizen of the United States, and resident of the borough of Manhattan, city, county, and State of New York, have invented certain new and useful Improvements in Resilient Heels, of which the following is a specification.

This invention relates to resilient heels and more particularly to the type known as half heels, or lifts made of rubber or other similar resilient material. More particularly, also, the invention relates to that type of lifts generally known as concavo-convex lifts.

Heretofore, it has been proposed to provide a concavo-convex lift, in which the concave surface is spherical, the lift being formed from a hollow sphere by cutting it along a line corresponding to the outline of a heel. The marginal edges of the attaching face of a concavo-convex lift as thus produced are curved from the rear edge of the lift to the breast corners and also between the breast corners. This particular lift has certain disadvantages which prevent it from being completely satisfactory.

One of these disadvantages is that while such a lift enables a tight contact to be obtained between the lift and the shoe heel along the marginal edges of the lift, the lift cannot be brought into close engagement with the shoe heel at other portions of its attaching face, due to the difficulty of flattening its spherically curved concave attaching face to a plane surface. Since the attaching faces of these lifts are of a spherical curvature with the peak at substantially the center of the lift, in order to bring the entire attaching face of the lift into contact with the shoe heel, it would be necessary to flatten arcs of circles extending in all directions from the central peak of the lift to its margin. It is impossible to flatten such arcs even approximately without driving the attaching nails closer together than is commercially practicable in a heel lift. My improved heel, on the other hand, is formed to present an attaching face having its marginal edge arranged in a plane, and having an outline such that when the lift is flattened against a shoe heel, its marginal edge from the rear edge to the breast corners will be substantially concentric or symmetrical with the outline of the heel.

Within its marginal edge, the attaching face of my improved lift constantly increases in depth longitudinally of the lift from its rear edge substantially to its breast edge. The transverse of the lift is such that each line of cross-section in parallel vertical planes will have a different curvature, but, as all these curvatures are transverse to the longitudinal center line of the lift and as the longitudinal curvature of the lift is slight, the nails that are applied will readily flatten out the transverse curvatures.

This and other features of my invention will be hereinafter further described, shown in the drawings and finally pointed out in the claim:

Figure 1 shows a perspective view of my improved lift with the deepest point at the central part of the breast line.

Figure 2 shows a diagrammatic view, indicating the central longitudinal curvature along the line 2—2 of Figure 1.

Figure 3 is a transverse vertical section taken on the line 3—3 of Figure 1.

Figure 4 is a diagrammatic view, showing the relation of the center point of the attaching face to the rear edge and the central point of the breast edge of the lift.

Figure 5 is also a diagrammatic view, showing the breast curvature of the lift.

Figure 6 is a view similar to Figure 2 of a modified form of lift.

Similar characters of reference indicate corresponding parts throughout the various views.

Referring to the drawing and more particularly to Figure 2, the line $e-e'$ indicates the marginal edge of the attaching face of the lift. From a point o which is the center of longitudinal curvature of the attaching face, an arc is shown extending from e' to the point g . A line $g-g'$ is shown drawn tangential to the arc $e'-g$ and extending for a distance equal to about one fourth or one fifth of the length of the arc $e'-g$, and the end of this line terminating at the point g' on the breast edge of the lift. The tangent line $g-g'$ is shown at right angles to the radius of curvature $g-o$. A line is shown extending from the point o to the horizontal line $e-e'$ and perpendicular to the line $e-e'$ forming with the radius line $o-g$ an angle α .

The broken line $m-p$ in Figure 2 represents the tread face of the lift, the portions

n—p and *m—n* of such face being preferably parallel to the arc *e'—g* and tangential portion *g—g'* respectively of the upper attaching face of the lift. The curved lines *g—h* and *k—n* are continuations of the arcs *e'—g* and *p—n* and indicate what the contour of the attaching and tread faces of the lift would be, if the longitudinal curvature of the rear portions of such faces was continued to the breast edge of the lift.

As before stated, the depths of transverse cross sections through the lift progressively increase from the rear edge of the lift to the breast line so that each lift has the deepest point of its attaching face at the central point of the breast line of the lift. Hence, when nails are applied and the lift is flattened, the curves corresponding to transverse sections of the lift are flattened and will bring about a tight joint at the marginal edge of the lift with the marginal edge of the heel, from the rear edge to the breast corners thereof.

In Figure 4, the line *d—c—f* represents the longitudinal center line, the line *a* indicates the plane of the marginal edge. The line *b* passes through the center point *c* of the attaching face of a lift such as is shown in Figs. 1 and 2. It will be apparent from Fig. 4 that the attaching face of the lift extends below the central point *c* on the line *b* to the point *f* which is the deepest point of the concave face of the lift. In Fig. 5, the points *e⁵*, *e⁶* are at the breast edges of the lift, and the curvature of the line *e⁵—f—e⁶* corresponds with the curvature of the breast line of the lift. It will be understood, of course, that Figs. 4 and 5 only indicate in diagrammatic form the relative positions of the parts referred to with reference to the lines *a* and *b*. In a practical lift, the curvature more nearly approximates that shown in Fig. 3.

By reference to Fig. 5 of the drawing it will be noted that a relatively deep transverse arc is obtained along the breast line of the lift, and, therefore, when this arc is flattened into a straight line against the heel face, a maximum tensional pressure of the side marginal edges of the lift at the breast against the heel face will be obtained.

In Figure 6 I have shown a modified form of the invention, in which the arc extending longitudinally of the attaching face of the lift is denoted by the line *e³—e⁴*, and in which the line extending from *o* to *e⁴* is perpendicular to the line *e³—e⁵* which represents the marginal edge of the attaching face. In this modification, the tangential portion *e⁴—e⁶* extends for only a relatively short distance beyond the curved portion *e³—e⁴* of the attaching face of the lift. In the form of lift shown in Fig. 6 as well as in that shown in Fig. 2, the depth at points

on the longitudinal center line of the lift increases toward its breast edge.

My improved lift is made of rubber or other similar resilient material, and substantially the entire lift is made of this resilient material, the thickness of the lift being that usually employed in lifts of this kind, such as is indicated in Figs. 1 and 3. Any well known practical means for attaching the lifts to the leather heels of shoes may be readily provided, and as this forms no part of the invention it is not shown in the drawing.

Lifts constructed in accordance with my invention have proved satisfactory in that they may be readily applied, and when the fastenings have been inserted and the lifts thereby attached to the heels, a very tight contact is secured along the marginal edge of the attaching face of the lift, extending from the rear end of the lift to its breast corners along the sides of the lift. Moreover, where lifts are made in standard sizes and these are applied to heels and are cut off or trimmed to conform to the exact size of the heels, the trimming line being substantially concentric with the outline of the lift. Consequently, the lift when trimmed has exactly the same structural elements that the initial lift had, namely, a longitudinal center line and transverse curvatures progressively increasing in depth from the rear end to the breast edge of the lift, the same structural elements cooperating together in exactly the same way, after the lift is trimmed.

I have described several embodiments of my invention but do not wish to be confined to details thereof, the spirit of my invention being defined in the appended claim.

I claim:

A resilient top-lift for a shoe heel of substantially uniform thickness and resiliency throughout and having a concave attaching face provided with a marginal attaching edge of heel shape and arranged in a plane, the longitudinal central line of the attaching face progressively increasing in depth from the rear edge of the lift to the breast line thereof in respect to the plane of the heel-shaped edge of the lift, the deepest point of the attaching face being at the center of the breast line, and the attaching face of the lift at any point in the length of the lift having a transverse curvature describing a single continuous arc.

In testimony that I claim the foregoing as my invention, I have signed my name in presence of two subscribing witnesses.

JOHN W. AYMAR, JR.
